UNITED STATES PATENT OFFICE.

WILLIAM W. JACKSON, OF PHILADELPHIA, PENNSYLVANIA, ASSIGNOR TO
MACKELLAR, SMITHS & JORDAN, OF SAME PLACE.

DESIGN FOR A FONT OF PRINTING-TYPE.

SPECIFICATION forming part of Design No. 12,561, dated November 1, 1881.

Application filed September 24, 1881. Term of patent 14 years.

To all whom it may concern:

Be it known that I, WILLIAM W. JACKSON, (assignor to MACKELLAR, SMITHS & JORDAN,) of the city and county of Philadelphia, Pennsylvania, have invented and produced a new and original Design for a Font of Printing-Type, of which the following is a specification.

The nature of my design is clearly shown in the accompanying typographic impression; and it consists of a heavy text letter ornamented by a series of short, light cross lines, as in the D, M, N, O, P, Q, U, V, W, and Y.

The character of the design is preserved in the lower case, save that the light cross-line ornamentation is omitted.

Having now described my invention, what I claim as new is—

The design for a font of printing-type, as shown and described.

WM. W. JACKSON.

In presence of—

WM. B. MACKELLAR,
HERMAN METIUS.
